UNITED STATES PATENT OFFICE.

S. HOWLAND RUSSELL, OF NEW YORK, N. Y.

SASH-BALANCE.

SPECIFICATION forming part of Letters Patent No. 297,720, dated April 29, 1884.

Application filed January 11, 1881. (No model.)

To all whom it may concern:

Be it known that I, S. HOWLAND RUSSELL, of New York city, New York, have invented certain new and useful Improvements in Devices for Raising and Lowering Window-Sashes, of which the following is a specification.

My invention relates to that class of devices for opening or closing the upper or lower sashes by means of cords passing over pulleys on the window frame and sashes, whereby the sash may be raised or lowered by pulling the cords. Several devices of this class have been heretofore produced, involving different arrangements of cords and pulleys and acting either on one or both sashes. One device of this character is shown in a former patent issued to me August 1, 1882, No. 261,877. In this latter patent I showed two cords, by pulling one of which the lower or upper sash might be opened, while the pulling of the other would raise or close the upper sash, whereas the lower sash was closed in the usual way by the direct action of the hand. In my present improvement, however, I provide one cord, termed the "opening-cord," which will enable either sash to be opened with a great mechanical advantage, owing to a compound-pulley arrangement of the cord, and in addition to this I use two other cords, termed "closing-cords," one of which enables the upper sash to be closed, and the other acts to close the lower sash. Clamps are arranged to hold either of the closing-cords, so that when the opening-cord is pulled it will open whichever sash is released by its clamp. This forms a comparatively simple arrangement of cords, which enables both sashes to be raised or lowered with ease, which is a more compact arrangement than any heretofore devised; and my invention therefore consists in the combined features here outlined, as hereinafter fully set forth.

In the drawings annexed, Figure 1 presents a front elevation of a window provided with my improved sash-operating devices. Fig. 2 is a vertical section thereof, and Fig. 3 a cross-section on line $\alpha\alpha$ of Fig. 2.

In these views, A indicates the window-frame; F, the lower sash, and G the upper sash, the said sashes being guided and bal-

anced in the window-frame in the usual manner.

Now, *a* and *c* indicate what I term the "closing-cords," and *b* the "opening-cord." 55 The opening-cord *b* hangs at one end free for manipulation at one side of the window, as indicated by the arrow, thence passes up to the top of the upper sash and over a sheave on a pulley, *d*, fixed to the top of the upper sash, thence around the top of said sheave and down to the top of the lower sash, where it passes around a pulley, *e*, fixed thereto, thence rises and passes over a second sheave on the upper pulley, *d*, and continues across the top of 60 the upper sash, and passes over and around a second pulley, *d'*, fixed on said sash, and thence down and around a second pulley, *e'*, on the lower sash, while its terminal end is finally fixed to the top of the upper sash or to 65 the frame of the pulley *d*; hence it will be seen that there are four loops in the opening-cord *b*, that two pass over the pulleys of the upper sash, and two around the pulleys of the lower sash. Consequently, by pulling down on 70 the cord *b*, as indicated by the arrow in Figs. 1 and 2, either the lower sash may be raised or the upper sash lowered, according as whichever of the closing-cords *a* *c* is freed, and the hand in thus pulling the cord will therefore 75 have a mechanical advantage of four to one over the sashes by reason of the compound-pulley arrangement provided by the four loops aforesaid; hence the sashes may be operated with great ease, which is of importance 80 in the case of heavy sashes in large houses or public buildings. 85

Now, *a* is the closing-cord which pertains to the upper sash, and *c* the closing-cord which pertains to the lower sash. This latter cord 90 *c* is fixed at one end to one side of the window-frame, as shown at *f* in Figs. 1 and 2, thence passes over pulleys *g g* on the top of the lower sash and continues down on the opposite side of the window, passing through or under a 95 clamping cam-lever, *h*, fixed on that side of the window-frame, and finally hangs free for manipulation. The cord *a* is fixed at one end to the top of the window-frame, as shown at *i* in Figs. 1 and 2, thence passes around or 100 under sheaves in the pulleys *d d'* of the upper sash, thence rises and passes over a pulley, *k*,

fixed to the top of the window-frame, and continues downward therefrom and passes under a second cam or clamp lever, *l*, fixed to the window-frame adjacent to the first clamp, *h*, 5 the end of the said cord hanging free for manipulation like the others.

Assuming, now, that both sashes are closed and the closing-cords *a c* drawn tight and the clamps *h l* depressed or tightened, so as to 10 firmly hold the cords, it will therefore be readily seen that neither sash can be opened without straining or breaking the cords *a c*, and hence the said cords form an additional safeguard in holding the sashes closed. If, 15 now, it is desired to open either sash, then the clamp is released on the cord of the sash which it is desired to open and the opening-cord *b* pulled down, when the sash thus released will be at once opened with a great mechanical ad- 20 vantage, as before described—that is, if the clamp *h* of the lower cord, *c*, is released, then the lower sash will be raised, whereas if the clamp *l* of the upper cord, *a*, is released, then the upper sash will be lowered; hence by this 25 arrangement one set of pulleys and cord acts on both sashes with great advantages. If both clamps are released, then both sashes may be opened to the desired extent by a proper ma- 30 nipulation of the cords *b* and *a*, as will be readily understood.

It will be seen that while the opening-cord *b* acts with an advantage of four to one on either of the sashes, the cords *a c* each act with an advantage of two to one on their respective 35 sashes; hence when both sashes are open the cords *a c* may be seized together and drawn down, when, their rates of motion being equal, both sashes will be simultaneously closed at one action. If desired, both free ends of the 40 cords *a c* may be connected together, forming a continuous loop for greater neatness or convenience. The opening-cord *b* may also be provided with a clamp like *h l*, so that the upper sash may be held suspended or open at 45 any desired adjustment by tightening said clamp on the cord; but it is not thought necessary. It will be also understood that any other form of clamp may be used to hold the cords *a c* besides the form of cam-levers shown. 50 Instead of having the opening-cord *b* in a double loop, engaging with two sets of pulleys on the sashes, whereby a quadruple ratio is obtained, it may be arranged in but one loop, to pass over one set of pulleys arranged at the 55 middle of the sashes, instead of at each side, and thus obtain a double ratio—that is, a ratio of two to one—but the quadruple arrangement is preferred.

Instead of employing clamps to hold the closing-cords of the sashes, clamps may be em- 60 ployed to hold the sashes themselves with like effect, as will be understood.

I am of course aware that various arrangements of pulleys and cords for operating the sashes besides that shown in my former pat- 65 ent have been heretofore devised. I am not, however, aware that an opening-cord has been heretofore used passing in a loop from a pulley on one sash to a pulley on the other sash, whereby both sashes are operatively engaged 70 by the same cord, and either of which may be opened by pulling said cord. I also believe that the clamps to hold the respective sashes closed, or to hold the closing-cords of said sashes in combination with the said opening- 75 cord, is peculiar to my invention, as is also the particular arrangement of the closing-cords and their pulleys.

It will be obvious that while I prefer to use the several features of my invention in com- 80 bination on the same window, yet they may be used separately, if desired.

Instead of pulling the ends of the cords di- 85 rectly by hand, a little reel may be employed for winding them up, if desired.

What I claim as my invention is—

1. The combination, with the window-frame and the upper sash, of the closing-cord *a*, fixed at one end to the frame depending in a loop therefrom, and passing under pulleys on the 90 upper sash, thence over a pulley, *k*, fixed to the frame, and thence depending therefrom for manipulation, substantially as and for the purpose set forth.

2. The combination, with a window-frame 95 and the lower sash, of the closing-cord *c*, fixed at one end to the frame, and passing over a pulley, *g*, on the sash, and thence depending for manipulation, substantially as herein set forth.

3. The combination, with a window-frame and its upper and lower sashes, of the two pulleys *d d'*, affixed to the top of the upper sash, and the two pulleys *e e'*, affixed to the top of the lower sash, with the opening-cord *b* fixed 100 at one end to one of the sashes, thence passing in successive loops over the respective pulleys, and finally depending for manipulation, substantially as and for the purpose set forth.

S. HOWLAND RUSSELL.
